Primary Examiner — Cynthia Ramirez*Assistant Examiner* — Michael A Maharajh(74) *Attorney, Agent, or Firm* — Don D. Cha; Hamilton DeSanctis & Cha, LLP(57) **CLAIM**

The ornamental design for a device for modulating speed in sports activity, as shown and described.

DESCRIPTION

FIG. 1 is a top perspective view of a device for modulating speed in sports activity showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.
